UNITED STATES PATENT OFFICE.

MORRIS MOSKOWITZ, OF NEW YORK, N. Y., ASSIGNOR TO UNITED STATES LIGHT AND HEATING COMPANY, OF NEW YORK, N. Y., A CORPORATION OF NEW JERSEY.

ELECTRIC REGULATOR.

No. 918,578.

Specification of Letters Patent.

Patented April 20, 1909.

Application filed March 14, 1908. Serial No. 420,999.

To all whom it may concern:

Be it known that I, MORRIS MOSKOWITZ, a citizen of the United States, and resident of the borough of Brooklyn, county of Kings, city and State of New York, have invented certain new and useful Improvements in Electric Regulators, of which the following is a specification, accompanied by drawings.

This invention relates to electric regulators, and the objects of the invention are to improve upon the construction and operation of such regulators, increase their efficiency, reduce sparking, and enable a large range of regulation to be obtained with small movement of the parts.

Further objects of the invention will hereinafter appear, and to these ends the invention consists of a regulator for carrying out all of the above objects embodying the features of construction, combination of elements and arrangement of parts, having the general mode of operation substantially as hereinafter fully described and claimed in this specification and shown in the accompanying drawings, in which,

Figure 1 is a front elevation of the regulator; Fig. 2 is a side elevation of the same; Fig. 3 is a longitudinal sectional elevation taken through the brush holder; Fig. 4 is a detail perspective view of the armature for one of the sets of magnets; Fig. 5 is a longitudinal sectional elevation of one of the magnets; Fig. 6 is a longitudinal sectional elevation taken through the dash pot; and Fig. 7 is a diagrammatic view illustrating the electric circuits for the regulator.

It will first be convenient to refer to Fig. 7, showing diagrammatically the circuits and arrangement of apparatus, from which the general construction and mode of operation of the invention will be understood. In Fig. 7, the regulator is shown applied to a car lighting system, in which the generator A is adapted to be driven from the axle, although this regulator, in accordance with my invention, may be used in any connection in which it is found applicable, for regulating a work circuit or for regulating the field of a dynamo electric machine. The regulator may be used either for constant potential or constant current regulation. In the system shown in Fig. 7, by way of illustration, a storage battery B is connected across the line and C represents the work

circuit with the lights or other translating devices D. The resistance R is connected in series with the work circuit through the conducting segments E and brush F. The brush as shown is carried by the cross link G which in turn is pivotally connected at each end of the substantially parallel vertically hung links H and I, which are adapted to be pivoted at their upper ends J and K to a suitable support. The links G, H and I are preferably of conducting material, in order to carry current to the brush F.

The links H and I are actuated or oscillated by means of the oppositely acting magnets L and M having cores or plungers O and P connected at each end to actuate said links H and I. A convenient mode of connecting the plungers O and P to the links is to provide pivoted cross heads or yokes Q and S on said links H and I to which the ends of the plungers O and P are rigidly but adjustably connected. As shown, the cross heads Q and S are pivoted to the links at the points T and U.

Any suitable form of magnets L and M may be provided, but I have chosen to show and use magnets provided with main windings V and W connected in parallel to each other across the brushes of the dynamo A. The magnets L and M are also provided with the auxiliary windings X and Y connected in parallel to each other across the brushes of the dynamo A and controlled by the controlling or relay magnet a connected across the line.

The circuits are as follows: From the positive brush of the dynamo A a wire 2 leads to the point 3 on the cross wire 4 which connects the upper ends of the links H and I. From thence the current passes down through the links H and I and through the cross link G to the brush F which bears upon the top of the segments E. This brush F is moved horizontally by the swinging of the links H and I and therefore a pin b slidably connects the link G with the brush as shown. The segments E are connected to sections of the resistance R and from said resistance a wire 5 leads to the lamps D. The other wire 6 of the work circuit leads back to the dynamo A. From the point 7 on the wire 2 a wire 8 leads to the point 9, from which main windings V and W of the magnets branch. These main windings are again connected together at the point 10.

and from thence a wire 11 leads to the point 12, from which a wire 13 connects with the wire 6 at the point 14. The auxiliary winding X branches from the point 15 and leads by wire 16 to the adjustable contact point 17. The auxiliary winding Y branches from the point 18 and leads by wire 19 to the adjustable contact point 20. The controlling magnet a is provided with 10 the pivoted armature c connected by the wire 21 with the point 22 which in turn is connected with the point 12 by the wire 23 and thus connects with the negative pole of the dynamo through wires 13 and 6. From 15 the point 24, adjacent the resistance R, a wire 25 leads to and through the controlling magnet a and thence by wire 26 to the point 22, and thence by wires 23, 13 and 6 to the negative pole of the dynamo, so that the 20 magnet a is a potential magnet and regulates for constant potential.

Auxiliary windings X and Y on the magnets L and M are wound to oppose the main windings V and W, so that either one or the 25 other of the magnets T and U will be neutralized according to which one of the auxiliary windings X and Y is included in circuit by the action of the controlling magnet a. If the armature c is in contact with the 30 contact point 20 as illustrated in Fig. 7, then a circuit will be complete from the positive brush of the dynamo A through both main and auxiliary windings W and Y on the magnet M and back to the negative 35 brush of the dynamo, so that magnet M will be neutralized. The auxiliary winding X of magnet L will be deenergized because the circuit of the same is broken at the contact point 17, but the main winding W of 40 magnet L will be energized and included in circuit, across the brushes of the dynamo. The magnet L will tend to draw its core O toward the left, as Fig. 7 is viewed, which will move the links H and I to the left and 45 will also move the core P of magnet M to the left. The brush F will be moved along the segments E and more resistance will be included in the circuits of the lamps D. If the core C of controlling magnet A is moved 50 into contact with the contact point 17, then the auxiliary winding X of magnet L will be energized, neutralizing said magnet and the auxiliary coil Y of the magnet M will be deenergized, so that the main coil W of 55 magnet M will tend to pull the core P to the right, as Fig. 7 is viewed, thus moving the parts of the regulator and the brush F to the right and cutting resistance out of the work circuit.

60 Obviously, the arrangement of windings on the magnets L and M is advantageous because the magnets are quick acting and sensitive, and also because sparking between the core C and contact 17 and 20 is practically eliminated, due to the neutralizing

effect of the differential windings on the magnets.

Figs. 1 to 6 on the drawings illustrate a mechanical construction of the regulator which is adapted to be connected in the circuits illustrated in Fig. 7. In Figs. 1 to 6, d represents a suitable backing or support of insulating material as slate or other suitable material. On this backing d are supported the parts of the regulator. At the top are arranged two brackets e suitably held in place as by means of the bolts f and screws g. Pivoted from these brackets e by means of the pins h are the vertical and substantially parallel links H 75 and I. The cross heads or yokes Q and S are pivoted in these links by means of the pivot pins T and U. The lower ends of the links H and I are connected by the cross link G pivoted at its ends to the vertical 80 links and provided intermediate its length with a bracket i carrying the vertical pin or member b. The insulated segments E are supported between clamps k secured to the backing d by means of the bolts l and 85 bound together by means of the longitudinal bolts n, passing through insulated sleeves m. A U-shaped brush holder o incloses the series of segments and carries the brushes which bear on the segments. As the links H and I oscillate, the lower cross link G will have a slight vertical movement which is accommodated by the sliding movement of the pin or member b moving vertically in the slot p in the end of the brush holder. The 90 upper and lower arms of the brush holder are recessed as shown in Fig. 3 and in the upper recess are arranged a plurality of brushes q in this instance two brushes being 95 shown. These brushes q are loosely held in position by the set screws r so that as the brush holder is moved horizontally along the segments a good contact is insured between the brushes q and the segments, for these brushes will accommodate themselves 100 to the surface over which they move. In the lower arm of the brush holder is arranged a brush s spring pressed by means of a spring t of any suitable form, preferably a leaf spring inserted between the brush and 105 the brush holder. This spring tends to push the brush s upwardly against the segments and forces the brush holder downwardly, so that the brushes q are pressed downwardly 110 upon the segments. According to this construction, contact is made on both sides of the segments to enable large currents to be handled. Preferably a bracket u is connected at the rear of the cross link G and a pin v on said bracket engages an aperture w 115 at the rear of the upper arm of the brush holder o, so that the brush holder is maintained in a position at all times substantially perpendicular to its direction of movement, and binding is avoided. The seg- 120

125

ments E extend rearwardly through the backing d at E' in order that the sections of the resistance R may be connected thereto.

Preferably arranged between the links H 5 and I are the magnets L and M supported in the iron casing x which in turn is carried on the studs y extending through the backing d. Within the casing x are arranged the brass spools z in which are wound the differential coils of the magnets V and X 10 for the magnet L, and W and Y for the magnet M.

The magnets L and M are preferably constant pull magnets of any suitable form, and 15 to this end I have shown tapering cores for the magnets and reversely tapered interior casings of iron. As shown, the core O of magnet L tapers in one direction and is provided with the reversely tapered casing or 20 sleeve O' inside of the spool z, while the core P of magnet M tapers in the opposite direction to that of the core O and is provided with the reversely tapered sleeve P' 25 inside of its spool z. According to this construction, the pull on either of the cores O and P is substantially constant irrespective of the position of the core in its magnet.

The ends of the cross heads or yokes Q and S are preferably screw threaded at 30 and pass through apertures 31 in the ends of the cores O and P. Adjusting nuts 32 on the screw threaded ends of the yokes permit a vertical adjustment of the cores, but rigidly hold the ends of the cores in predetermined position with relation to the yokes. 35

In order to prevent binding during the oscillating movement of the links H and I, studs 33 are provided on the casing x and disks or rollers 34 are carried by said studs 40 and arranged between the sides of the link G, bearing against the interior surfaces of said sides as illustrated in end view in Fig. 2.

A suitable dash pot is provided for damping the movements of the regulator and in 45 this instance, the dash pot comprises the casing 35 having plugs 36 screw threaded into its ends. These plugs are in turn supported on the brackets 37 on the casing x by means of the screws 38. The dash pot 50 casing 35 is provided with an open top formed by a lip 39 above the level of the top of the body of the casing, so that the casing may be filled with oil, but will not spill over. In the casing 35 is a double 55 ended plunger 40 provided with an aperture 41 to receive the vertical pin or finger 42 carried by the cross rod 43 which in turn is pivoted at each end to the brackets 44 on the links H and I. The pin 42 is adapted to 60 slide vertically in the aperture 41 in the plunger 40, to accommodate the slight vertical movement of the cross rod 43 as the links H and I are oscillated by the magnets L and M.

65 The controlling magnets c are suitably

supported from the backing d by means of the bolts 46. The magnet a is provided with a core 47 and the armature c which is carried by the spring c' at one end, preferably of phosphor bronze secured to the bracket 48 which in turn is connected to the backing d as by means of the screws 49. The edges of the armature c are grooved at 50 to enable a weight bracket or holder 51 to engage the armature c by means of the set screws 52 70 and be adjusted along the length of the armature. The shank 53 of the bracket 51 is preferably screw threaded and provided with a nut 54 to hold the weights W' 75 in place. The outer end of the armature c is 80 provided with the spring 55 connected at one end 56 to the armature and having the other end 57 bent upwardly and over the end of the armature and bearing against an adjusting screw 58 carried by the bracket 59. The 85 adjustable contact point 20 is carried by the bracket 60 and the adjustable contact point 17 is carried by the bracket 61. These contact points 17 and 20 are preferably of platinum or other suitable material. The 90 spring 55 is provided with the aperture 62 of sufficient diameter to permit the contact point 17 to pass therethrough without touching the spring, and also large enough to prevent the spring from bearing against the 95 bracket 61. According to this construction of the armature c, the spring 55 prevents the armature from jarring back and forth between the contacts 17 and 20 and insures accurate regulation and control. 100

I claim and desire to obtain by Letters Patent the following:

1. In a regulator, the combination of substantially parallel links, a cross arm pivotally connected to the lower ends of said links, cross heads or yokes pivoted to said links, a pair of opposing magnets arranged side by side within said links, cores or plungers for said magnets connected at each end to said cross heads, means controlled by the swinging movement of said links, and means for controlling the energization of said magnets. 105

2. In a regulator, the combination of a series of insulated segments, a U-shaped brush holder for the same, a plurality of brushes loosely held by one arm of said holder, a spring pressed brush held by the other arm, and means for actuating said holder along the segments. 115

3. In a regulator, the combination of vertically hung swinging links, magnets for actuating the same, a dash pot and plunger, a cross arm connecting said swinging links, and a finger connected to said cross arm and movably connected with the plunger of said dash pot. 125

4. In a regulator, the combination of a pair of normally opposing magnets provided with auxiliary neutralizing coils, 130

means for energizing one or the other of said coils to neutralize one of said magnets, vertically hung swinging links, cores or plungers connected to said links, a cross link, and means connected to be operated by said cross link.

5. In a regulator, the combination of a pair of substantially parallel vertical freely swinging links, a cross link pivotally connecting said vertical links, a pair of oppositely acting magnets, cores or plungers for said magnets pivotally connected at each end to said links, and means controlled by said links.

6. In a regulator, the combination of a pair of opposing magnets, freely swinging vertical links at each end of said magnets, cores for said magnets connected to move said links, a cross link pivotally connected to said vertical links, and a brush connected to be operated by said cross link.

In testimony whereof I have signed this specification in the presence of two subscribing witnesses.

MORRIS MOSKOWITZ.
